UNITED STATES PATENT OFFICE

MARY E. O'HEARN KELLEHER, OF RUTLAND, VERMONT

MOTOR DRIVEN THREAD CUTTER

Application filed March 17, 1931. Serial No. 523,352.

The invention aims to provide an exceptionally simple and inexpensive, yet a rapid and desirable cutter for threads, ravellings and cloth, which may be driven at will by an electric motor.

The device embodies a stationary cutter having a notch to receive the thread or other material to be cut, and a rotary cutter lying against said stationary cutter, said rotary cutter being mounted upon the shaft of the electric motor, but if desired, said rotary cutter could be mounted upon a rotatable shaft other than a motor shaft. In either instance, another object of the invention is to provide novel means for tightly holding the rotary against the fixed cutter.

A still further aim is to provide a fixed cutter attached in a novel manner to the base of an electric motor.

Yet another aim is the provision of a unique guard to overcome liability of personal injury.

With the foregoing in view, the invention resides in the novel subject matter herein-after described and claimed, description being accomplished by reference to the accompanying drawings.

Fig. 1 is a perspective view.

Fig. 2 is a side elevation with the guard 30 in section.

Fig. 3 is an end elevation.

Fig. 4 is a transverse sectional view on line 4—4 of Fig. 2.

Fig. 5 is a detail longitudinal section on line 5—5 of Fig. 3.

A preferred construction has been illustrated and will be specifically described, with the understanding however, that within the scope of the invention as claimed, variations may be made.

An electric motor 6 is shown having an arched supporting base 7 which is provided with attaching feet 8. I have shown these feet secured by screws 9 to a wooden base 10 whose lower side is padded as at 11 to prevent scratching of articles of furniture upon which it may rest. Also mounted upon the base board 10 is a switch 12 for controlling the electric motor, and the current supply wires 13 leading to said switch, may be pro-

vided with the conventional means for connecting them with an electric light socket.

A rotary cutter 14 having radial cutting arms 15, is mounted upon the shaft 16 of the motor 6, and said cutter 14 may be slidably keyed upon said shaft, as denoted at 17. The cutter 14 is provided with a flat outer side, and a flat vertical cutter plate 18 lies against said flat side, said plate being formed with a notch 19 through which the threads or other material to be cut, are inserted into the path of the arms 15. The lower end of the plate 18 is integral with a horizontal base bar 20 which extends under the crown portion of the arched base 7 and is secured to the latter by screws or the like 21.

A vertical pressure plate 22 rises from the base bar 20 and is provided at its lower end with a finger 23 received somewhat loosely in an opening 24 formed through said base bar. The upper end of the plate 22 is formed with an opening 25 through which the shaft 16 passes, and at opposite sides of said shaft, said plate carries bearing balls 26 which engage the inner end of the rotary cutter 14. A bolt 27 passes through aligned openings in the fixed cutter plate 18 and in the pressure plate 22, and by tightening the nut 28 of said bolt, the pressure plate 22 may be so adjusted toward the fixed cutter plate 18 as to insure proper contact between the cutter arms 15 and said plate 18.

A suitable arched guard 29 embraces the cutter plate 18 and the opposed hub 30 of the motor 6, the lower end of said guard being provided with spring fingers 31 which engage the base bar 20 to hold the guard in place. The front of the guard 29 is formed with a notch 32 registering with the notch 19, the two notches jointly forming a throat across which the thread or the like to be cut, is placed to be acted upon by the co-acting rotary and fixed cutters. The guard 29 cooperates with adjacent portions of the device in forming a casing having the throat 19—32, and the rotary cutter 14 sweeps across a portion of said throat to perform the desired cutting operation.

It will be seen from the foregoing that although the device is exceptionally simple and

inexpensive, it will be highly efficient and desirable for cutting threads, ravelings, cloth, etc. While the details disclosed may be considered as preferred, attention is invited to 5 the fact that within the scope of the invention as claimed, numerous variations may be made.

I claim:—

1. A device of the class described comprising an electric motor having a base and a horizontal shaft above said base, a rotary cutter carried by said shaft, a stationary vertical cutter plate lying against the outer side of said rotary cutter and having a thread-receiving notch, a horizontal base bar carrying said vertical cutter plate, and means securing said base bar to the motor base; together with a vertical pressure plate connected at its lower end with said base bar and having bearing means at its upper end engaging said rotary cutter, and means engaging said pressure plate and said stationary cutter plate for moving the former toward the latter to maintain contact between the two cutters. 20

2. A device of the class described comprising an electric motor having a base and a horizontal shaft above said base, a rotary cutter carried by said shaft, a stationary vertical cutter plate lying against the outer side of 30 said rotary cutter and having a thread-receiving notch, a horizontal base bar carrying said vertical cutter plate, and means securing said base bar to the motor base; together with an arched guard embracing said vertical cutter plate and having spring fingers at its lower end engaging said supporting bar. 35

3. A device of the class described comprising a cutter plate having a notch, a rotary cutter lying against one side of said plate and having cutting arms to sweep across said 40 notch, a shaft carrying said rotary cutter, a pressure plate having an opening through which said shaft passes, said pressure plate having bearing means adjacent said opening 45 engaging the inner side of said rotary cutter, and means for moving said pressure plate toward said stationary cutter plate. 100

4. A device of the class described comprising a cutter plate having a notch, a rotary cutter lying against one side of said plate and having cutting arms to sweep across said 50 notch, a shaft carrying said rotary cutter, a pressure plate having an opening through which said shaft passes, said pressure plate having bearing means adjacent said opening 55 engaging the inner side of said rotary cutter, a base carrying said stationary cutter plate, the lower end of said pressure plate being connected with said base, and means for moving said pressure plate toward said stationary cutter plate. 110

5. A device of the class described, comprising an electric motor whose shaft projects beyond one end of the motor housing, 60 a fixed casing mounted at said end of said

motor housing around said projecting shaft end; said casing having an outer end wall at right angles to the shaft, a peripheral wall laterally spaced from said shaft and forming with said outer end wall a right angular corner for the casing, and a notch in said corner to receive a thread or other article to be cut; and a rotary cutter carried by said projecting shaft end within said casing and operable across said notch. 70

6. A device of the class described, comprising an electric motor having a base and a horizontal shaft above said base, a right angular metal bar having a horizontal end secured to said base and a vertical end extending upwardly beyond said shaft, said vertical bar end being disposed in a plane at right angles to the shaft and having a notch in one edge, and a rotary cutter carried by said shaft and contacting with the inner side of said vertical bar end, said cutter being operable across said notch. 80

In testimony whereof I affix my signature.
MARY E. O'HEARN KELLEHER.
